UNITED STATES PATENT OFFICE.

MATTHEW A. WALKER, OF SOUTH CONNELLSVILLE, PENNSYLVANIA.

SHELL FOR MACHINE-GUNS.

1,338,802.

Specification of Letters Patent. Patented May 4, 1920.

Application filed December 8, 1919. Serial No. 342,075.

To all whom it may concern:

Be it known that I, MATTHEW A. WALKER, a citizen of the United States, residing at South Connellsville, in the county of Fayette and State of Pennsylvania, have invented a new and useful Shell for Machine-Guns, of which the following is a specification.

The invention has reference to improvements in projectiles, and it is the primary object of the invention to provide a projectile having means to enable the projectile to be handled and transported without the danger of the same exploding.

A further object of the invention is to provide novel means to guide the firing pin to insure the firing of the shell, when the firing pin contacts with the target at which the same is fired.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a fragmental elevational view partly in section of a shell constructed in accordance with the present invention; and

Fig. 2 is a sectional view taken on line 2—2 of Fig. 1.

Referring to the drawing in detail, the reference character 5 designates the projectile body which is of the usual construction, the forward end of which includes a sleeve 8 to accommodate the base 10 of the percussion fuse, forming an important feature of the invention. This percussion fuse includes the base 10 and the hollow body portion 11, the latter being threaded as at 12 to permit the same to be readily secured to the base 10 after the explosive material has been positioned therein, this construction being necessary to permit the elements of the percussion cap to be readily assembled.

An end section 13, which is frusto-conical in formation, is removably secured to the body portion 11, by means of the threaded extension 14, cooperating with the threads 15 formed in the upper end of the body 11.

Disposed within the member 13, at a point adjacent the base thereof, is the annulus 16, which is secured to the inner walls thereof in any suitable manner, so that the shoulder 17 presented thereby will support the firing pin 18, which is of a conical formation, and of a diameter slightly less than the interior diameter of the frusto-conical member 13 to permit the same to move freely within the member 13, when the firing pin 18 contacts with the target at which the same is fired.

From an observation of the drawing, it will be seen that the outer end of the firing pin 18 extends beyond the end of the member 13 to insure the pin contacting with the object at which the same is fired, to the end that the lower extremity 19 thereof will contact with the cap 20.

This cap 20, is positioned within the upper end of the metallic chamber 21, which embodies comparatively light material, the same being of a size to closely fit within the body portion 11 to insure against movement thereof with relation to the body portion, 30 which movement might result in the exploding of the explosive material contained within the metallic chamber 21, the upper portion of the chamber being constructed to properly support the cap 20. 35

In operation, the firing pin 18 is supported by the band 16, so that the lower extremity 19 of the firing pin 18 is normally held in spaced relation with the cap 20, the band 16 being constructed to support the firing pin in such position under ordinary conditions.

It is the purpose of the invention to provide a band capable of supporting the firing pin 18, in its normal position under ordinary conditions and to prevent the firing of the shell if the device is dropped, or otherwise caused to contact with a surface, the same being constructed to fire only under unusual pressure directed thereto. 100

Having thus described the invention, what is claimed is:—

In a projectile, a body portion, a hollow body removably secured to the body portion and having a threaded extension providing 105 a shoulder, said hollow body adapted to support high explosive material, and a firing cap, a frusto-conical member having an opening including inclined walls and having a threaded portion, a shoulder forming a 110

part of the frusto-conical member, said threaded portion adapted to be positioned on the threaded extension, an annulus clamped between the shoulders, a tapering 5 firing pin supported within the opening in the frusto-conical member and having a shoulder engaging the annulus, and said firing pin adapted to be wedged within the opening of the frusto-conical member, when

the latter is positioned on the hollow body 10 portion.

In testimony that I claim the foregoing as my own I have hereto affixed my signature in the presence of two witnesses.

MATTHEW A. WALKER.
